UNITED STATES PATENT OFFICE.

GERRITT SMITH, OF ASTORIA, AND THEODORE F. TAYLOR, OF BROOKLYN,
NEW YORK.

TELEGRAPHY.

SPECIFICATION forming part of Letters Patent No. 284,498, dated September 4, 1883.

Application filed May 19, 1882. (No model.)

To all whom it may concern:

Be it known that we, GERRITT SMITH and THEODORE F. TAYLOR, citizens of the United States, residing, respectively, in Astoria, in the county of Queens, and in Brooklyn, in the county of Kings, both in the State of New York, have invented certain new and useful Improvements in Duplex Telegraphy, of which the following is a specification.

10 In transmitting two or more sets of signals simultaneously in opposite directions over one and the same telegraphic conductor, according to the method heretofore usually practiced, much interference and confusion arises from 15 false signals which are produced upon the receiving-instrument by currents of charge and discharge, the origin of which is due to the electro-static or inductive capacity of the line. This phenomenon manifests itself in a 20 marked manner when the line is of considerable length and is well insulated, and under these conditions it also acts to prevent the transmission of signals in rapid succession—as required, for example, in the operation of 25 the automatic or rapid system—the tendency of the inductive action being to abnormally lengthen the separate signals, and to cause them to be blended together, and thus to become indistinct and illegible. The means heretofore 30 employed for the purpose of obviating this practical difficulty have usually consisted in appliances either for neutralizing the electro-static charge upon the line-wire, or for counteracting its effect by artificially inducing a 35 charge at the terminal station, and causing this to act simultaneously, but in an opposite sense, upon the receiving-instrument.

Our invention differs in its general character from others hereinbefore referred to, in that 40 we employ the electro-static charge, instead of the dynamic current, as a means for operating the receiving-instrument, thereby utilizing the inductive capacity of the line as the active agent for the transmission of signals.

45 To this end our invention consists, essentially, in the employment, in connection with any suitable apparatus for duplex or multiple telegraphy, of a condenser of considerable electro-static capacity interposed between the 50 junction of the main and artificial lines and

the earth at each terminal station, and we also interpose another similar condenser in the artificial line, which latter, instead of being placed between the main line and the earth at the home station, as in the manner heretofore practiced, has both its terminals united with the main line on opposite sides of the transmitting-battery. By reason of this organization both the main and artificial lines are wholly insulated from the earth at each 60 terminal station, and we are enabled to transmit the necessary signals in both directions by merely altering the distribution of the electro-static charge in the system.

The accompanying drawing is a theoretical 65 diagram illustrating a duplex telegraph arranged for simultaneous transmission from both terminal stations.

Referring to the figure, K represents the transmitting-key at one terminal station. We 70 prefer to make use of a double-current key, which transmits a current of one polarity when it is depressed and of the opposite polarity when it is raised. This result may be effected by means of any one of a number of devices. 75 We have illustrated a simple form, in which two independent batteries, E' and E'', of equal electro-motive force, but opposite polarity, are permanently connected, respectively, with the front and rear contacts of the key, the opposite poles of the batteries being united and connected to one terminal of a condenser, C, having a capacity approximately equal to that of the line L, the other terminal of which is connected to the earth at G. A wire, 1, extends from the lever of the key K to the point 2, where it divides into two branches, one branch going through the rheostat l to the point 3, where it unites with the main line L, and the other branch going through the rheostat a to the point 4, where it unites with the 80 artificial line A.

The receiving-instrument M, which may be an electro-magnetic, electro-chemical, or other well-known and suitable apparatus for the purpose, is shown as placed in a bridge-wire, 3 4, between the main and artificial lines, whereby it is rendered neutral to outgoing impulses; or, as a well-known substitute for this arrangement, the bridge-wire 3 4 may be dispensed 85 90 95 100

with and a differential electro-magnetic receiving-instrument may be employed, the opposing coils of which are respectively included in the wires 2 3 and 2 4, having the same relation thereto as the rheostats l and a in the figure.

The artificial line A consists, essentially, of a rheostat, between which and the point 5 an equating-condenser (of a capacity which may be much less than that of the main line L) is interposed. It is preferred to construct this rheostat in two or more sections, as shown at r' , r^2 , and r^3 in the figure, these being united in multiple arc to the conductor leading from the main line at 2. Between each rheostat-section and the opposite terminal, 5, of the artificial line a section of the condenser is interposed, as shown at c' , c^2 , and c^3 .

The effect of employing a sectional rheostat and sectional condenser is the same as if a single rheostat and single condenser of equal capacity were used; but the division into sections in the manner shown enables them to be more conveniently and accurately adjusted for the purpose of rendering the electro-static capacity and time of charge and discharge of the artificial line the same as that of the main line.

The terminal section at the opposite end of the line L has its apparatus arranged in precisely the same manner as that already described.

It will be obvious from an inspection of the diagram that the main line and the artificial line at each station are electrically insulated from the earth by the interposition of the condensers, and hence the transmission of signals may be effected simply by varying the distribution of the electro-static charge of the main and artificial lines and of the condensers attached thereto or forming a part thereof, the office of the latter being not only to increase the normal electro-static capacity of the line, thereby increasing the strength of the electro-static impulses, but also to govern the distribution of the total electro-static charge.

The operation of the apparatus is as follows: When the key K is depressed, in order to transmit a signal, a positive charge from the battery E' passes over the wire 1 (which virtually forms a portion of the main line) to the point 2, where it divides, one portion going through the rheostat l and main line L to the condensers C' c^4 c^5 c^6 at the distant station. The receiving-instrument M' at the home station, being placed, as hereinbefore explained, in the bridge-wire 3 4, or otherwise arranged so as to be rendered neutral to outgoing impulses, is not affected thereby; but at the distant station that portion of the charge which enters the condensers c^4 , c^5 , and c^6 passes through the receiving-instrument M' and produces a momentary positive signal. If, now, the key K be raised, a negative impulse from the battery E' is transmitted over the line in like manner, and produces a momentary negative

signal upon the receiving-instrument M'. Thus it will be understood that the transmission of the electric impulses in this manner from either end of the line does not affect the home instrument, but only the instrument at the distant station, and that although the impulses, whether positive or negative, are only momentary, yet if a suitable receiving-instrument—such as the well-known polarized relay—be employed, the armature, having been thrown into one position by a positive impulse, will remain there until thrown back again by a negative impulse; hence the signals of the ordinary Morse code may be transmitted in this manner without difficulty, as the action of the receiving-instrument will be the same as if prolonged electrodynamic currents were employed.

The combined resistance of the rheostats r' , r^2 , and r^3 , constituting the essential portion of the artificial line A, should be approximately equal to the resistance of the line L; but the condensers c' c^2 c^3 may be of correspondingly less capacity. It is advantageous in most cases to construct the said rheostats of unequal resistances, so that the total resistance of the artificial line may be more conveniently adjusted to correspond with the variable resistance of the main line L, which in turn depends upon conditions of insulation, due to changes in the weather, &c.

Our improved system is particularly well adapted for rapid automatic telegraphy, and when used for this purpose an automatic transmitter of any suitable character—such, for instance, as a pattern-strip perforated with two rows of holes—is substituted for the key K, and a corresponding electro-chemical or other receiver is placed at M. The principle of operation is precisely the same as that hereinbefore explained.

We claim as our invention—

1. The combination, substantially as hereinbefore set forth, with a main line, of a battery and key at the home station, a condenser interposed between said battery and the earth, an artificial line having one of its terminals united with the main line and the other with the line-terminal of said condenser, thus spanning said key and battery, and a condenser interposed in said artificial line.

2. The combination, substantially as hereinbefore set forth, with a main line, of a battery and key at the home station, a condenser interposed between said battery and the earth, an artificial line having one of its terminals united with the main line and the other with the line-terminal of said condenser, an equating-condenser interposed in said artificial line, and a receiving-instrument placed in such a relation to the main and artificial lines as to be rendered neutral to outgoing electrical impulses.

3. The combination, substantially as hereinbefore set forth, with a main line, of a battery and key at the home station, a condenser interposed between said battery and the earth,

an artificial line having one of its terminals
united with the main line and the other with
the line-terminal of said condenser, thus span-
ning said key and battery, an equating-con-
denser interposed in said artificial line, and a
5 receiving-instrument interposed between a sec-
ond condenser and the main line at the distant
station.

In testimony whereof we have hereunto sub-
scribed our names this 16th day of May, A. D. 10
1882.

GERRITT SMITH.
